AUSTRALIA.

TWO-CYCLE INTERNAL-COMBUSTION ENGINE.

1,423,578.

Specification of Letters Patent. Patented July 25, 1922.

Application filed July 23, 1918. Serial No. 246,289.

To all whom it may concern:

Be it known that we, ARTHUR GEORGE LLOYD NEIGHBOUR and HARRY CECIL WYNNE NEIGHBOUR, subjects of the King of Great Britain, residing at "Biwa" North Road, Brighton, in the State of Victoria, Commonwealth of Australia, have invented new and useful Improvements in Two-Cycle Internal-Combustion Engines, of which the following is a specification.

This invention relates to improvements in two-cycle internal combustion engines, and it has been particularly devised to provide means whereby the explosive charge, which has been previously compressed either in the engine crank case or by an auxiliary pump, is transferred to the working cylinder so as to give smooth entry thereto without throttling; means whereby the intermingling of the incoming charge with the exhaust gases is reduced and means whereby a free exit for the latter is provided with improved scavenging of the cylinder.

A further object of the invention is to obtain a more certain firing of weak mixtures and improved running at low speeds.

The invention, moreover, provides removable means for readily obtaining access to the inlet and exhaust ports to facilitate the removal of carbon deposit therefrom.

The essential features of the invention comprise a piston, the head of which is made conical in shape and has formed therein a passage extending from a port at the side of said piston to a central hole at the top of said conical head, the incoming charge being adapted to pass through the passage to the said central hole and being thereby axially directed to the top of the engine cylinder.

Furthermore, the invention provides a cylinder head so shaped that when the entering charge impinges centrally thereon it is smoothly directed outwardly around said cylinder head and is then turned downwardly and inwardly into the cylinder, driving before it the burnt gases which strike upon the sides of the conical piston head and are thereby diverted outwardly through an exhaust port of ample area.

In internal combustion engines of this type, as ordinarily constructed, the piston towards the end of the power stroke uncovers a port in the cylinder wall through which

the exhaust gases escape. Shortly afterwards and just prior to the piston reaching the end of the power stroke it uncovers a second port, termed the transfer port which is usually situated on the opposite side of the cylinder so as to lie as far away from the exhaust port as possible.

The explosive charge which has been compressed in the crank case by the piston during the power stroke, or has been compressed by an auxiliary pump, passes through the transfer port into the cylinder. The entering charge partly drives out the remaining exhaust gases.

To reduce mixing of the entering charge with the exhaust gases, the piston is provided with a deflector situated adjacent to the said transfer port. The said deflector, which is made in a variety of shapes of greater or less efficiency, directs the incoming charge up the side of the cylinder towards the top. The piston then rises up compressing the charge, which is fired at the end of the stroke in the ordinary way.

In the present invention the same cycle of operations is followed, but the parts are so constructed and arranged that a free and unimpeded entry and circulation of the entering charge to the cylinder is obtained which effectively scavenges the same, increases the efficiency, and improves the operation of the engine.

In order that the invention may be more readily understood reference will now be had to the accompanying explanatory drawings, wherein:

Figure 1 is a view in vertical section of a two-cycle engine, wherein the piston is shewn at the end of the power stroke.

Figure 2 is a similar view to Figure 1 and wherein the piston is shewn at the end of the compression stroke.

Figure 3 is a view in transverse section through the exhaust port taken on the line 3-3 in Figure 1.

Figure 4 is a view in perspective of the piston.

Figure 5 is a fragmentary view in vertical section of the door for cleaning the piston passage and is drawn to a larger scale.

Figure 6 is a face view of the door shewn in Figure 5.

Figure 7 is a fragmentary view in vertical

section shewing the cylinder head fitted with heated-tube ignition.

Figure 8 is a similar view to Figure 7 shewing the cylinder head fitted with heated-chamber or automatic ignition.

In these drawings like characters of reference denote the same or corresponding parts in the different views and the numeral 1 designates the cylinder of a two-cycle internal 10 combustion engine wherein a piston 2 is adapted to reciprocate. The head 3 of this piston 2 is made conical in shape and is provided at its apex with a central circular hole 4. This hole 4 is connected by a passage 5 15 in the piston head to an opening or port 6, preferably rectangular in shape, in the side of the piston 2. The passage 5 is made to gradually change in shape from the rectangular port 6 to the circular hole 4 as indicated by broken lines in Figure 4.

Shortly before the end of the downward or power stroke of said piston 2 the port 6 therein uncovers the transfer port 7 in the side of the cylinder 1 which is connected by 25 a transfer passage 8 formed in the wall of the said cylinder 1 with the crank case 9, or with an auxiliary pump (not shewn) when the latter is employed. Said transfer port 7 and transfer passage 8 are likewise of rectangular shape to conform with the shape 30 of the piston port 6.

At the end of the power stroke of the piston 2 the ports 6 and 7 are in exact alignment, and the piston passage 5 and the 35 transfer passage 8 combine to form a smoothly curved continuous upward passage having a bend therein of ample radius.

The explosive mixture which has been compressed in the crank case 3 by the downward stroke of the piston 2, or by an auxiliary pump, passes upwardly through this continuous passage and is thereby smoothly directed without choking or throttling from the crank case 9 to the apex of the conical 45 piston head 3.

The entering charge in consequence issues with high velocity from the aforesaid central circular hole 4 and is axially projected to the top of the cylinder 1 in the form of a 50 divergent conical jet as indicated by arrows in Figure 1.

The passage 5 can be made of uniform area from end to end thereof, or it can be gradually constricted more or less in area 55 towards the central hole 4, thereby permitting the velocity of the said conical jet to be increased to a desired extent.

The cylinder head 10 is provided with a central downwardly depressed conical boss 60 11, and the walls of the cylinder head 10 surrounding said boss 11 are curved outwardly and downwardly to the part of the cylinder head 10 of maximum internal diameter.

The maximum internal diameter of the

cylinder head 10 is preferably somewhat greater than the diameter of the said cylinder 1, which makes the latter easier to bore in manufacture, and the walls of said cylinder head 10 below the part thereof having the greatest internal diameter are inclined 70 inwardly and downwardly to meet the upper end of the cylinder 1.

The conical jet after axially ascending the cylinder 1 impinges upon said central conical boss 11 and the incoming mixture is thereby smoothly directed on all sides around the cylinder head 10 and by the latter is again directed downwardly and projected inwardly into the cylinder 1, as shewn by arrows in Figure 1. 80

The descending charge displaces the burnt gases downwardly and the latter strike upon the sides of the conical piston head 3 and are thereby deflected laterally through the exhaust port 12 which has been opened a 85 little in advance of the transfer port 7 by the upper edge of the piston 2 which forms the base of the conical piston head 3.

The high velocity of the central conical jet, which has a free and unimpeded circulation in the cylinder 1 combined with the curved shape of the cylinder head 10 produces whirling or turbulence of the charge in the combustion chamber 13 which experiment has shewn to be necessary to ensure 95 rapid combustion at high engine speeds.

The combustion chamber 13 is an annular space of approximately circular section formed by the curved cylinder head 10 and the sloping sides of the piston head 3 as 100 shewn in Figure 2.

The inward projection of the descending charge into the cylinder 1 by the inwardly inclined sides of the cylinder head 10 effectively expels the burnt gases and prevents 105 loss of explosive mixture through the exhaust port 12, which might occur if the charge passed downwardly along the sides of the cylinder 1 in a thin stream.

The conical piston head can be made with 110 conical sides as indicated by the broken lines in Figure 4, but the sides thereof are preferably made to curve downwardly and outwardly, as shewn. By being so constructed they more efficiently turn aside the 115 descending burnt gases through the exhaust port.

The exhaust port consists of a series of openings 12 made around the cylinder 1 with their top edges lying in a plane at right 120 angles thereto so that all of said openings 12 are simultaneously opened and closed by the piston 2 as it reciprocates. The openings 12 extend for a considerable distance around the cylinder 1 but not so far as to 125 lie in the path of the port 6 of the piston 2 as the latter reciprocates. Said openings 12 can be made parallel to the axis of the cyl-

inder 1, but they are preferably made in sloping positions as shewn in Figures 1 and 2 whereby they are enabled to better direct the outgoing gases, and said openings on both sides of the central one are also curved in a horizontal plane for this purpose as shewn in Figure 3.

We are aware that a ring of openings around a cylinder forming an exhaust port is old and well known and no claim is made for such arrangement.

The openings 12 communicate with a groove 14 extending a required distance around the outside of the cylinder 1 and lying between radially projecting flanges 15 integrally formed with said cylinder 1. The upper of said flanges 15 forms the bottom of the water jacket 16 as is shewn in Figures 1 and 2.

The groove 14 is closed at its ends by vertical ribs 17 formed integrally with and connecting the flanges 15 and it is provided with a cover 18 to form an exhaust chamber 19. Said cover 18 is so constructed that the exhaust chamber 19 gradually converges into a circular outlet 20 of ample area, and it is furnished with a flange 21 to which the exhaust pipe (not shewn) is attached.

In two-cycle engines of small size the exhaust port is apt to become more or less choked by carbon deposit, which must be removed from time to time, and it is therefore desirable that access be readily obtainable to said port. For this purpose recesses 22 are formed around the flanges 15 into which the cover 18 is fitted. Internally projecting lugs 23 formed near the ends of the cover 18 are provided with studs 24 which extend through holes in said ribs 17 and are fitted with nuts 25. Upon removal of these nuts 25 the cover 18 can be easily taken off laterally in the direction of the arrow in Figure 3 thereby giving ready access to the openings 12 for cleaning purposes. When the cover 18 is replaced the nuts 25 are tightened up to firmly fix said cover 18 again in position. If desired, suitable packing (not shewn) can be inserted between the edges of the cover 18 and the inner end of said recesses 22.

In order to obtain access to the piston passage 5 for cleaning purposes an opening 26 formed in the wall of the transfer passage 8 is normally closed by a gas-tight cover 27 which can be removed whenever it is desired to clean said passage 5.

It is important when removing carbon deposit that the latter should be prevented from falling through the transfer passage 8 into the crank case 9 and in order to provide for this a hinged door 28 is located within said opening 26. The inner side of this door 28 conforms to the shape of the passage 8 and said door 28 is provided with

hinge pintles 29 which rest in recesses 30 formed in the sides of said opening 26.

In order to fix the upper end of said door 28 in position there are formed on the outer side thereof lugs 31 in which a pin 32 is detachably fitted, the ends of said pin normally resting in recesses 33 formed in the sides of said opening 26.

In operation, the cover 27 is removed and the door 28 is opened outwardly to permit the pin 32 to be withdrawn laterally from said lugs 31. The door 28 is then pushed inwardly to rest upon the inner wall of the passage 8, as shown in Figure 5, thereby giving ready access to the piston passage 5. After cleaning said passage 5 the door 28 is again opened outwardly, the pin 32 re-inserted in said lugs 31 and said door 28 is then returned to its normal position and the cover 27 is replaced.

The removable covers 18 and 27, moreover, provide convenient access to the ports 6 and 7 and the openings 12 during manufacture, allowing said ports and openings to be accurately adjusted as by filing, and enabling perfect timing of the transfer and exhaust operations to be easily obtained.

When the explosive mixture is compressed in the crank case 9 prior to its transference to the cylinder 1 it is drawn into said crank case 9 by the vacuum produced therein by the ascent of the piston 2, either through a port 34 which is uncovered by the piston at the end of the compression stroke as in Figure 2 or through an automatically or mechanically operated valve in said crank case 9. These devices are well known and form no part of the present invention. The port 34 is shewn directly beneath the exhaust outlet 20 for convenience of illustration, but said port 34 can be located at some other preferred part of the circumference of cylinder 1 as will be readily understood.

The sloping sides of the piston head 3 combined with openings 12 enable a very free exhaust to be obtained. This is most essential in this form of engine as the dwell of the piston at the end of the power stroke being of very brief duration it is of the utmost importance that the pressure in the cylinder should rapidly fall to that of the atmosphere in order to provide sufficient time for the entering charge to displace the residual gases and efficiently scavenge the cylinder.

Ordinarily in engines of this class the incoming charge passes vertically up the transfer passage and is then diverted more or less horizontally through the transfer port into the cylinder and is immediately afterwards turned vertically up the side of the cylinder by the deflector on the piston which adjoins said port. These sudden changes in direction retard the free entry of

the charge into the cylinder, thereby reducing its velocity and diminishing its scavenging effect. Moreover the exhaust gases are frequently pocketed behind the ordinary deflector and are thereby retained in the cylinder resulting in a decrease of the volumetric efficiency of the engine.

The transfer port 7 is not uncovered by the piston 2 in the usual way, but communicates with the interior of the cylinder 1 by way of the passage 5 in the piston head 3, as hereinbefore described, and the said transfer port 7 lies further down the cylinder 1 than the exhaust port.

One or more piston packing rings 35 is or are arranged between the upper edge of said piston 2 and the port 6 therein. At the end of the power stroke of the piston 2 and during the period of exhaust of the burnt gases and entry of fresh explosive charge the piston ring or rings 35 is or are situated between the said transfer and exhaust ports, as shewn in Figure 1, thereby preventing leakage from the former to the latter port.

Owing to the disposition of the ports 6 and 7 and the passage 5 and the exhaust openings 12 the entering charge is enabled to drive out the residual gases as above described, thereby obtaining an approximately end to end scavenging of the cylinder 1 without added complications of extra passages, valves, and other parts.

The transfer passage 8, piston passage 5 and exhaust openings 12 can all be made of ample area to allow their functions to be rapidly performed and thereby permit an increase of piston speed with corresponding increase in the length of stroke.

The top of the said conical piston head 3 lies at some distance above the base thereof, so that while the transfer of the fresh charge from the crank case 2 or auxiliary pumping cylinder (not shewn) to the engine cylinder 1 is taking place the risk of intermingling with the residual burnt gases, and the escape of entering charge through the exhaust openings 12 is greatly reduced, especially as the said charge is centrally directed to the top of the engine cylinder 1.

The conical piston head 3 is far easier to machine than the piston head provided with a deflector, and it may be turned and polished without difficulty.

In practice, it is found that carbon will not deposit readily on smooth polished surfaces. Consequently the deposition of carbon on the piston head 3 which is apt to occur in two-cycle engines may thereby be largely obviated, especially as the sloping sides of the piston head 3 are swept by a downward rush of the escaping exhaust gases.

When the piston 2 reaches the end of the

compression stroke as shown in Figure 2 65 the conical central boss 11 projects downwardly into the circular central hole 4 at the apex of the piston head 3 but not so far as to contact therewith.

The source of ignition may be electric, hot 70 tube, or heated chamber.

When electric ignition is employed the sparking plug 36 is screwed centrally into the boss 11 and the spark gap 37 is located so that it enters the aforesaid hole 4 at 75 the apex of the piston head 3.

When a tube 38 heated by a burner 39, or a chamber 40 which is initially externally heated and thereafter maintained at a high temperature by the heat of the explosions is used as a source of ignition the orifice 41 leading therefrom passes centrally through the boss 11 and the lower end thereof is likewise adapted to enter the hole 4 at the apex of the piston head 3. These 85 forms of ignition are old and well known and in themselves form no part of the invention.

The said central hole 4 at the apex of the piston head 3 and the passage 5 leading 90 thereto contain explosive mixture which cannot become diluted with burnt gases, and when the piston 2 reaches the end of the compression stroke, the said contained mixture is brought directly into contact with the 95 source of ignition.

Firing of the charge is thereby greatly facilitated and rendered more certain, improving the operation of the engine at slow speeds or when using weak mixtures, the effect of the dilution of the charge by burnt gases being then more pronounced.

Owing to the location of the means of ignition as above described, the compressed explosive mixture is ignited at approximately 105 the centre of the space it occupies, the explosion quickly spreads radially therefrom to all parts of the combustion chamber 13 and thereby ensures rapid firing with corresponding increase of efficiency.

It will be obvious to persons skilled in the art that the ordinary simple type of two-cycle internal combustion engine arranged and constructed according to the present invention will be thereby improved in operation and rendered more efficient without in any way adding to its complexity and cost.

The two-cycle engine above described and illustrated in the drawings is of the marine type, but the same construction can be employed in two-cycle engines for motor vehicles, or in stationary two-cycle engines for industrial purposes. Moreover the invention can be applied to engines having horizontal or inclined cylinders, or cylinders 125 disposed in other preferred positions.

Explosive mixture has been described as passing into the cylinder 1 from the piston

passage 5, but air alone may similarly enter the cylinder 1 to scavenge it, the fuel being injected under pressure through a jet 42 at the end of the compression stroke in the ordinary way, as will be readily understood.

What we do claim is:—

1. A two-cycle engine comprising a cylinder, a conical boss projecting inwardly and axially from the cylinder and ignition means in said conical boss, an annular combustion chamber of curved cross-section centrally disposed around said conical boss and having a maximum diameter greater than the cylinder diameter, the 10 annular wall of the combustion chamber being inclined inwardly to the cylinder wall, a transfer port and a transfer passage in the wall of the cylinder, an annular series of exhaust openings in said 15 cylinder wall, a hinged door and a detachable gas-tight cover permitting access to said transfer passage, a detachable casing enclosing said exhaust openings, an exhaust outlet in said detachable casing, a piston in 20 said cylinder, a conical extension on said piston, a port at the side of said piston, a central hole in the apex of said conical extension, a passage connecting the said hole and the said port, and one or more packing 25 rings in the piston between the exhaust openings and the transfer port when the piston is at the end of its power stroke, substantially as described.

2. In a two-cycle engine, a cylinder, a 30 transfer passage in said cylinder, a transfer port at the end of said transfer passage, an exhaust port in said cylinder arranged oppositely to said transfer port, an annular combustion chamber of curved cross section at the 35 end of said cylinder, said combustion chamber having a maximum diameter greater than the cylinder diameter and having a sloping wall inclined inwardly to the cylinder wall, a conical boss projecting inwardly and axially into said combustion chamber, a piston in said cylinder having a conical head, a port in the side of the piston, an opening at the apex of the conical head, an inlet passage in said conical head connecting said opening 40 with the port in said piston, and ignition means in said boss arranged so as to project into said opening at the end of the compression stroke, substantially as described.

3. In a two-cycle engine, a cylinder, 45 initial compressing means, a transfer passage in said cylinder connecting the latter with said initial compressing means, a transfer port in the cylinder wall at the end of the transfer passage, a series of exhaust openings in said cylinder arranged oppositely to said transfer port, a conical boss projecting inwardly and axially from the cylinder end, ignition means in said boss, an annular com-

bustion chamber of curved cross section centrally disposed around said boss and 50 having a maximum diameter greater than the diameter of said cylinder, a piston in said cylinder, an inlet passage forming an initial combustion chamber in said piston, and a port in the side of the piston at the 55 end of the inlet passage, said inlet passage and said transfer passage being arranged to form a continuous upwardly curved passage at the end of the power stroke, and said exhaust openings being situated so as not to be in 60 the path of the port in the side of said piston, substantially as described.

4. In a two-cycle engine, a cylinder, a conical boss projecting inwardly and axially from the cylinder end, ignition means in 65 said conical boss, an annular combustion chamber of curved cross-section centrally disposed around said conical boss and having a maximum diameter greater than the cylinder diameter, the annular wall of the combustion chamber being inclined inwardly to the cylinder wall, substantially as described.

5. In a two-cycle engine, a cylinder, a transfer port and a transfer passage in the 70 wall of said cylinder, an annular series of exhaust openings in the wall of said cylinder, a hinged door and a detachable gas-tight cover permitting access to the said transfer passage, a detachable casing enclosing 75 the said exhaust openings, and an exhaust outlet in said detachable casing, substantially as described.

6. In a two-cycle engine, a cylinder, a transfer passage in said cylinder, an opening in the outer wall of said transfer passage, a door in said opening, hinge pintles on 80 said door, lugs on the outer side of said door, a pin in said lugs and recesses in the opposite sides of said opening for said hinge pintles 85 and the ends of said pin and a gas-tight detachable cover on said opening, substantially as described.

7. In a two-cycle engine, a cylinder, an exhaust port in said cylinder, flanges extending partly around said cylinder, a groove between said flanges, ribs formed at the ends of said groove, a detachable cover fitting said recess, internally projecting lugs formed on 90 said cover, studs in said lugs passing through 95 holes in said ribs, nuts on said studs, an opening in said cover and a flange around said opening, substantially as described.

In testimony whereof we affix our signatures in presence of two witnesses.
